UNITED STATES PATENT OFFICE.

JOHN COATES, OF ERIE, PENNSYLVANIA.

WATER-MOTOR.

SPECIFICATION forming part of Letters Patent No. 267,672, dated November 21, 1882.

Application filed March 10, 1882. (No model.)

To all whom it may concern:

Be it known that I, JOHN COATES, a citizen of the United States, residing at Erie, in the county of Erie and State of Pennsylvania, have 5 invented new and useful Improvements in Water-Motors; and I do hereby declare that the following is a full, clear, and exact description thereof, reference being had to the accompanying drawings and the letters or figures 10 of reference marked thereon.

My invention relates to the construction of water-motors, and particularly to that class of water-motors known as "piston-motors."

The particular object of my invention is to 15 construct a water-motor which is peculiarly adapted to operate the bellows of organs. My device, however, is not restricted in its use to the purpose named, but may be used as a motor for general purposes.

20 The especial nature of my improvements and the scope of my invention will fully appear in the following general description thereof and the subjoined claims.

My device is illustrated in the accompanying 25 drawings, as follows:

Figure 1 is a longitudinal vertical section, with some parts in elevation, the line of section in this figure being the line $z z$ in Figs. 2 and 3. Fig. 2 is a transverse vertical section 30 on the line $x x$ in Fig. 1, the parts beyond being in elevation. Fig. 3 is a plan view of the under side of the cover of the bed A. Fig. 4 is a detail of construction. Fig. 2 also shows the connection of the inlet-valves of the supply-pipe with the organ.

The various parts are indicated by letters of reference, as follows:

A is the base of the machine, and contains the valves and valve-gears within its chambers 40 A'. B is the cylinder; B', the piston-chamber; B², the piston; B³, the piston-rod. C is the valve-chamber; C', the valve; 1 2 3 4, the passages in the valve; d d', the passages from the valve-chamber to the passages leading to the piston-chamber; D, the supply-passage; c e, the exhaust-passages; P P', the passage to the upper end of the cylinder; P², the passage to the lower end of the cylinder. p p' are the ports. g' is a tappet-arm on the piston- 45 rod. g g are adjustable tappet-collars on the valve-rod. G² is the valve-rod or tappet-rod.

G' is the valve-crank; G, the valve which regulates the movement of the piston in the auxiliary cylinder from which the main valve is moved. E is the said auxiliary cylinder; e, 55 the piston-stem of said auxiliary cylinder; C², the crank-arm of the main valve. D' D² are inlet-valves in the supply-pipe. O is the organ; M, the organ-bellows. L is the winch by which the organist opens the supply-valve 60 D'. K is a cord connecting said valve with said winch. I is a weighted arm regulating said valve D'. J is the weight on said arm. I' and J' are similar devices on the valve D². K' is a cord connecting the arm I' with the 65 bellows M. F is the supply-pipe for the cylinder E. H is the valve-chamber of this cylinder; H' H, the water ways or passages, and h the exhaust.

The construction is as follows: The main 70 cylinder, B, sits on the base A in a vertical position. It is provided with a passage, P, which conveys the water to and from the upper port, p. The lower port, p', is in the top of the base. On the under side of the top of 75 the base the casting is extended down so as to bring the valve into proper position, and thus are formed the chambers P' P², which are in fact parts of the passages to the ports p and p'. The main valve C' is an oscillating plug- 80 valve. It is mounted at one end on its stem as a journal and at the other end on a pivot-pointed adjusting-screw, N, which holds it so as not to bind or wedge in its chamber. It is provided with D's or passages 1 2 3 4, of which 85 1 is the supply D, 2 and 3 are exhaust D's, and 4 is the back chamber, and is connected with the supply D by a vent or passage, V, which allows the water to fill the chamber 4 and keep the valve balanced. C is the main valve chamber or chest, and has openings c c for the exhaust, and d d' for connecting with the passages P, P', and P². It also has an opening into the supply passage or chamber D. The valve is moved by an arm or lever, C². The 90 water exhausted from the valve-chamber enters the chamber A' in the base A, and finally passes off through a pipe, a. By this arrangement the exhaust is very free and no back-pressure will occur.

The mechanism for moving the main valve is as follows: An auxiliary motor, E, is at-

tached to the cover of the base A, and lies at right angles to the main valve. (See Fig. 3.) This motor is provided with an oscillating valve, G, which is shown in dotted lines in Fig. 1, and it is operated by an arm or lever, G', which is connected with the tappet-rod G². Water is supplied to this engine from the supply of the main engine by the pipe F. The piston-rod e of this auxiliary motor connects with the arm C² of the main valve, and hence as this engine is operated the main valve is oscillated. The time of movement of the auxiliary motor is regulated by the position of the collars g g on the tappet-rod, and as they can be adjusted as desired the length of stroke of the main piston can be regulated. The object of the auxiliary motor is to secure a full movement of the valve by a tappet device and prevent the valve C from stopping while its faces are passing the ports of the valve-chamber, which it would do if the tappet-rod were connected directly or by levers with the arm C², for the reason that the water has no expansive power, and as soon as the pressure is stopped, (as it is the instant the faces of the valve get opposite the ports,) the source of power—viz., the head of water—is cut off from action upon the piston and the motor stops. If the motor were operating machinery which would run past the point by momentum it would be able to pass its faces over the ports; but in an organ-blower this could not well occur, and the advantage of this construction is that the main piston-rod B³ changes its movement from one direction to the other without any perceptible jar or jerk.

The mechanism for regulating the supply of water to the motor is as follows: D' and D² are throttles in the supply-pipe, one of which is connected by a cord with the winch L, or some other suitable device on the organ, which is accessible to the organist, the other throttle is connected to the organ-bellows. These throttles are weighted similar to a safety-valve on a boiler, and unless held open by the cords will be kept shut by the weight. The throttle connected with the bellows is so connected therewith that when the bellows are collapsed the throttle will be open, and when the bellows are inflated the throttle will be closed. The other throttle is opened or closed at will by the organist. The result of this construction is that when the organist opens the throttle D' the motor will be set in motion, and if the bellows get pumped full the other throttle, D², will be closed and stop the motor, thus avoiding all danger of bursting the bellows in case the organist fails to stop the motor when he stops playing upon the organ, or when the consumption of air is less than the supply. When my motor is used for running a gas-machine the second throttle can be connected with the gasometer and serve as a governor, the same as in the present instance.

In Fig. 4 a detail of construction is shown. It consists of a friction-bearing upon the tappet-rod to keep it from falling of its own weight. The bearing is pressed against the rod by a spring, the tension of which is regulated by a screw.

The object in placing the valve at one end of the cylinder of the main motor is to get as speedy an exhaust as possible by utilizing the weight of the water. This position of the valve would be of no special advantage if the cylinder was horizontal. Another advantage of this position of the valve is that it can be located in the chamber A', and the exhaust from the valve-chamber can be clear and free into a large open space, in place of into a narrow duct, and thus back-pressure is avoided.

What I claim as new is—

1. In a water-motor, the combination, substantially as shown, of the following elements: a base having therein a chamber, a cylinder mounted upon said base, a valve for supplying water to and exhausting it from said cylinder, arranged within said chamber, a secondary motor for operating said valve, also arranged within said chamber, and, finally, a valve-gear for operating the valve of said secondary motor from the movements of the main motor.

2. In a water-motor, the combination, substantially as shown, of the following elements: the hollow base A, with discharge a, the cylinder B, with ports connecting with said hollow base, a valve for supplying water to and exhausting it from said cylinder, placed within said base, a secondary motor arranged within said base, and connected with said valve by the rod e, and having a valve, G, with arm G', and, finally, the tappet-rod G² and tappet-arm g'.

3. In a water-motor, the valve C', with D-chambers 1 2 3 4, and vent or passage V, substantially as and for the purposes set forth.

4. The combination, with the supply-pipe of a water-motor, of two throttles or shut-off valves, D' D², having cords for the purpose set forth, of mechanism which, when valve D' is opened, opens and closes throttle D², for the purpose set forth.

5. The combination, with the supply-pipe of a water-motor, of two throttles or shut-off valves, D' D², the first operated by hand and the second by the action of the mechanism to which it is attached, as and for the purpose set forth.

In testimony that I claim the foregoing I have hereunto set my hand this 4th day of March, 1882.

JOHN COATES.
